BRISTLE INSERTING APPARATUS

Almer C. Wright, 162 Norman, Clyde, Calif., assignor
of one-half to William B. Thomas, Concord, Calif.

Filed July 31, 1961, Ser. No. 128,120

8 Claims. (Cl. 300—8)

This invention relates to apparatus for inserting bristles into broom shoes and is particularly directed to a device for facilitating the ready replacement of bristles in wire brooms.

The bristles of wire brooms as employed on street sweepers and the like commonly wear out after a relatively short period of use. Where the brooms are used on concrete, the bristles wear out after approximately 30 hours. Unfortunately the replacement of the bristles of a wire broom as heretofore conducted by hand is a tedious and time consuming operation, it requiring of the order of 8 hours for one person to fill one broom. A very extensive bristle replacement program is hence required to maintain wire brooms in proper condition for sweeping service.

It is an object of the present invention to provide apparatus for replacing the bristles of a wire broom in a substantially automatic fashion whereby the time required for bristle replacement is greatly minimized over that of previous hand methods.

Another object of the invention is the provision of apparatus of the class described that picks up wire broom straws, automatically bends them in half, and drives them through the holes of a broom shoe.

It is still another object of the invention to provide apparatus of the class described which is adjustable to handle a variety of shoe sizes.

It is a further object of the invention to provide apparatus of the class described wherein the spacing between the doubled over bristles can be adjusted to fit a variety of distances between broom shoe holes.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

FIGURE 1 is an elevational view of the apparatus with the bristle inserting means thereof in position to pick up bristles or straws,

FIGURE 2 is a sectional view taken at line 2—2 of FIGURE 1, the bristle inserting means being omitted,

FIGURE 3 is an enlarged portional sectional view of the bristle inserting means of the apparatus in engagement with the bristles prior to bending thereof,

FIGURE 4 is a sectional view taken at line 4—4 of FIGURE 3,

FIGURE 5 is a sectional view of the inserting means of the apparatus with the bristles in folded condition ready for insertion into a shoe,

FIGURE 6 is a portional top plan view of FIGURE 5,

FIGURE 7 is a sectional view taken at line 7—7 of FIGURE 5, and

FIGURE 8 is a sectional view similar to FIGURE 5, but illustrating the injection of the bristles into the shoe.

Considering now the invention in some detail and referring to the illustrated form thereof in the drawings, there is provided apparatus for inserting bristles into a broom shoe which includes a bristle inserting head 11 slidably mounted along a guide 12. The head may be reciprocated in any suitable manner such as by hand or power means. As here shown, reciprocation is effected

2

by pneumatically operated means such as a pneumatic cylinder 13. The head carries a bristle locking device 14 having a claw 16 which is selectively engageable with bristles 17 supported in a holder 18 at the lower extent 5 of the head stroke within the guide channel. The claw is manipulated into engagement with the undersides of the bristles at an intermediate position and an upward stroke of the head is initiated. The claw thus pulls the bristles into the guide and in so doing doubles them over. 10 Spacing between the doubled over bristles is maintained as they are pulled upwardly through the guide by bristle spacing and guiding means 19 at the lower end of the guide 12. When the head reaches the upper end of the stroke, the locking device 14 is manipulated to disengage 15 the claw from the bristles. The guide is then aligned with the holes of a brush shoe 21 secured to support arms 22 and a downward stroke of the head is initiated. The bristles are thus forced downwardly through the guide and injected into the holes of the brush shoe, proper bristle spacing being maintained by the bristle spacing 20 and guiding means 19.

As regards the preferred structure of the apparatus generally outlined above, the guide 12 is preferably of an elongated rectangular form including a longitudinally 25 extending channel 23 of rectangular cross section with a narrower longitudinal slot 24 extending centrally exteriorly therefrom (see FIGURE 7). The guide 12 is secured to the upper end of a support standard 26 by universal joint means 27 which facilitates pivotal movement about vertical and two right angularly related horizontal axes as well as translation along one horizontal axis. More specifically, the joint means comprises a mounting member 28 journaled to the upper end of the standard 26 for rotation about a vertical axis. The 30 member 28 includes a horizontal bore 29 receiving a shaft 31, the shaft being hence rotatable as well as translatable within the bore. The channel guide 12 is then pivotally secured as indicated at 32 to an end of the shaft for rotation about an axis transversely thereof. The universal joint 27 thus facilitates extreme flexibility of movement of the channel guide relative to the standard which as will be subsequently apparent is necessary in the alignment of the bristles with the holes of a brush shoe.

The head 11 is preferably provided as a block 33 having a cross section commensurate with that of the channel 23 and with an ear 34 at its upper end projecting outwardly through the slot 24. The lower end face of the block is provided with a slight V-notch 36, as best shown in FIGURE 6, to facilitate ready engagement with the bent over end of the bristles. In addition the block 35 is provided with a central longitudinally extending slot 37 adjacent its lower end and in alignment with the channel guide slot 24.

The slot 37 in the head block 33 facilitates journaling 55 of the claw 16 of lock device 14. The claw is of generally C-shaped configuration with the upper leg thereof pivotally secured at its end within the slot 37. Thus the claw may be pivoted between positions wherein its web projects through the slot and its lower leg is exteriorly of and substantially parallel to the channel guide, 60 as depicted for example in FIGURE 1, and wherein the web is parallel to the guide axis and the lower leg projects through the slot and across the channel. To facilitate such pivotal movement, the locking device further includes an operating lever arm 38 pivotally secured to the ear 34 of the head block. A link arm 39 is pivotally connected at one end centrally of the lever arm 38 and at the other end to the web of the claw adjacent its lower end. An inverted J-shaped hook member 41 is pivotally secured at the end of its long leg to the lever arm at the position of the pivotal connection of the link arm 39 thereto. Finally, a spring 42 is secured 65

between the mid length region of the long leg of the hook member and the ear 34. Thus when the lever arm 38 is pivoted upwardly to a stable off dead center position relative to the spring 42, the claw is pivoted to its position wherein the lower leg is external to the channel 5 guide. When the lever arm is pivoted downwardly to another stable off dead center position, the claw is pivoted to its position wherein the lower leg projects across the channel of the guide and the short leg of hook member 41 engages a notch 43 in the ear 34 of the head block (see FIGURE 3).

The pneumatic cylinder 13 is mounted at the upper end of the channel guide in alignment therewith as by means of a bracket 44 projecting therefrom. The piston 46 of the cylinder is then secured as by threadable attachment to the head block. The ports of the cylinder are connected by air lines 47, 48 to a suitable valve 49 mounted at the base of standard 26 and which is in turn connected to a compressed air inlet line 51. The valve 49 is preferably solenoid actuated and electrically connected to a foot pedal actuating switch 52 mounted upon the base of the standard. The switch may be arranged for example as by means of limit switches (not shown) to actuate the valve 49 to produce incremental motion of the piston 46 and head block 33 in a single direction responsive to each actuation of the foot pedal switch until the entire stroke is completed. Thereafter, actuation of the foot pedal produces reverse motion of the piston and head. By virtue of the foregoing arrangement and inasmuch as the cylinder is foot actuated, substantial hand manipulation of the bristles as they are injected into the brush shoe is facilitated.

The bristle holder 18 is preferably provided as an elongated rectangular open-topped box member secured to the standard 26 as by means of brackets 53 at a position subjacent the lower end of the channel guide when it is in vertical position. More specifically, the holder extends transversely of the channel guide axis and the center of the holder is aligned therewith. The front side and bottom of the holder are open at their center as indicated at 54 and the rear side has a central recess 56 coextensive with the front and bottom opening. The bristles 17 placed in the holder thus straddle the opening 54. Hence when the head block 33 is at the lower extent of its stroke in contact with the bristles, the lever arm 38 of the locking device may be actuated to pivot the lower leg of the claw 16 through the opening of the holder and beneath the bristles. The bristles are thus centrally clamped between the claw and end of the head such that when the head and claw are moved upwardly through the channel, the bristles are bent over the claw by virtue of their engagement with the channel sides.

The bristle spacing and guiding means 19 which maintain a suitable spacing between the doubled over bristles as they are pulled into the channel and guide the bristles into the holes of the shoe during injection preferably includes a spacing member 57 mounted on a spring steel arm 58 or equivalent means at the lower end of the channel guide on the opposite side thereof from the slot 24. The spacing member 57 is normally urged by the arm 58 through a central longitudinal slot 59 in the lower end of the guide across the channel therethrough so as to separate the bent over bristles as they are moved through the channel. However, the member 57 is shaped such that it is urged outwardly through the slot 59 by the head block when the latter contacts the spacing member. Thus the member is moved to an unobstructing position when the looped over end portion of the bristles passes same. In addition a pair of rollers 61 are journaled upon arms 62 pivotally attached to the opposite sides of the guide, the rollers being movable through side openings 63 in the guide into engagement with the opposite exterior sides of the bent over bristles in the channel. The arms 62 are spring loaded to normally urge the rollers inwardly whereby the opposite legs of the bent

over bristles are restricted between the rollers and spacing member 57. Of course the spacing between the legs of the bristles is readily varied by the employment of spacing members of varied thickness. Hence, broom shoes wherein the spacing between holes is varied can be readily accommodated.

Finally, the support arms 22 for holding the shoe 21 to be serviced are pivotally attached to circumferentially spaced brackets 64 projecting from the standard 26 subjacent the bristle holder 18. The arms have apertures 65 through their ends for receiving mounting bolts 67 normally provided at the opposite ends of the shoe 21. Inasmuch as the arms 22 are pivotal, they may be adjusted to a variety of circumferential spacings to thus accommodate a number of different sized shoes.

In the operation of the bristle inserting apparatus, a broom shoe 21 is first fastened to the arms 22 and the holder 18 is filled with bristles 17. The channel guide 12 is positioned parallel to the standard 26 with its lower end closely adjacent the bristles in the holder, movement of the guide being facilitated by universal joint 27. Assuming the head 11 to be at the lower end of the guide in contact with the bristles, as shown in FIGURE 1, the operating lever 38 of the locking device 14 is pivoted downward to position the lower leg of the claw 16 beneath the bristles in the holder as indicated in FIGURE 3. The spacer member 57 is at this time out of the channel due to the head abutting and forcing same outward against the loading of the arm 58. The foot switch 52 may now be depressed to actuate the cylinder 13 for upward movement of its piston and the head block 33. The bristles 17 are pulled upwardly into the channel 23 and in so doing are doubled over the claw 16. When the head block and claw surpass the spacing member 57, it moves inwardly through the slot 59 and across the channel 23 between the bent over bristles. The spacing member and the rollers 61 bearing against the exterior sides of the bristles thus maintain a proper spacing therebetween. When the head reaches the upper end of the channel guide and the bristles are pulled all of the way up thereinto, the piston and head are stopped. Now the channel guide is manipulated, by virtue of the movement permitted by universal joint 27, into alignment with the particular holes in the shoe 21 to be filled with the bristles in the channel. In this connection the lower end of the guide is positioned closely adjacent the shoe as shown in FIGURE 8. The lever 38 is now pivoted upward to disengage the hook 16 from the bristles. The foot switch 52 is depressed to initiate downward movement of the head, the bristles being urged by the head downward into the shoe holes. Where necessary the bristles may be further guided by hand alternately or simultaneously with depressions of the foot switch so as to manipulate the bristles through the holes. The foregoing procedure is repeated until all holes of the shoe are filled.

What is claimed is:

1. Bristle bending and inserting apparatus comprising an elongated guide having a channel longitudinally therethrough and a longitudinal slot extending exteriorly from said channel, said channel having longitudinally extending spaced guide walls, a head slidably mounted for reciprocation within said channel, means coupled to said head for controllably effecting said reciprocation, a locking device carried by said head for movement therewith including a claw pivotally mounted for movement through said slot for selective positioning within the channel for longitudinal movement therein, an elongated open topped bristle holder disposed subjacent said guide and formed to support unbent bristles of greater length than the distance between said walls in transverse relation to the axis of the guide, said holder having a central opening coextensive with said slot and channel and located in the path of movement of said claw whereby said claw is movable through said opening to engage the un-

derside of the bristles so that upon longitudinal movement in one direction of the head the claw will draw the bristles between the walls of the channel, in longitudinal alignment therewith thereby folding said bristles into opposed folded portions, said head being movable in the opposite direction and adapted to engage the folded bristles and move them longitudinally out of said channel.

2. Bristle bending and inserting apparatus comprising an elongated guide having longitudinally extending spaced guide portions, a head slidably mounted for reciprocation within said guide, means operatively connected to said head for effecting said reciprocation, a bristle holder for retaining bristles of greater length than the distance between said guide portions, supporting means for a broom shoe having bristle receiving apertures, means mounting said guide for selective movement between positions overlying said holder in generally transverse relation to bristles carried therein and in adjacent alignment with the apertures of a broom shoe when carried by said supporting means, a bristle engaging device carried by said head including a claw selectively engageable with the undersides of bristles carried by said holder and movable longitudinally in said guide away from said holder to draw said bristles between said spaced portions of said guide in longitudinal alignment therewith thereby folding said bristles into opposed folded portions having their ends directed away from said head, said head being movable toward said supporting means and engageable with said bristles to move them longitudinally out of said guide with said bristle ends being directed toward aligned broom shoe apertures.

3. Bristle bending and inserting apparatus comprising, means defining a generally elongated channel, means movable along said channel in one direction for engaging unbent bristles disposed generally transversely to said channel at a point intermediate their ends and for pulling said bristles into said channel in generally longitudinal alignment therewith to fold said bristles about said points into opposed folded portions, said channel having a width smaller than the length of said unbent bristles, means movable along said channel in an opposite direction for urging the folded bristles longitudinally out of said channel, and spacing means for maintaining the opposed folded portions of each bristle in spaced relation as the bristles are moved out of said channel.

4. Bristle bending and inserting apparatus comprising a guide member defining a generally elongated channel therein, bristle engaging means mounted for reciprocating movement along said channel and including a portion disposed slidably in said channel for longitudinal movement therein with said means, said means further including a claw member selectively positionable in said channel in spaced relation to said portion and being longitudinally movable in said channel with said means, said claw being adapted to engage unbent bristles disposed generally transversely to said channel and fold over said bristles between said claw and said portion by pulling them into said channel in general longitudinal alignment therewith upon movement of said means in one direction, said channel having a width smaller than the length of

60

the unbent bristles, said portion being adapted to engage folded bristles disposed in said channel and move them out of said channel upon movement of said means in the opposite direction, and means for moving and holding the claw out of the channel while said portion is moving the bristles out of the channel.

5. Bristle bending and inserting apparatus comprising, an elongated guide member having a longitudinally disposed channel therein extending to one end of the guide member, a head member slidably mounted in said channel for longitudinal reciprocating movement therein, means for selectively reciprocating said head member, said head member having a bearing portion for engaging bristles disposed longitudinally in said channel to push them longitudinally out of said channel at said end of the guide member, a bristle engaging claw mounted on said head and having a portion selectively movable into said channel in spaced relation to said head bearing portion, said claw being positionable in end alignment with said channel at a position spaced from said end of the guide member, said claw being movable with said head from said position towards said guide member and into the channel for longitudinal movement therein away from said end.

25 6. Apparatus as described in claim 5 further defined by a bristle spacing member disposed adjacent said end of said guide member and mounted for selective positioning in longitudinal alignment with the path of said claw portion in said channel, said head member adapted to urge said spacing member out of the path of said claw portion when the latter is disposed in said position thereof.

35 7. Apparatus as described in claim 6 further defined by a pair of spaced guide elements disposed on opposite sides of said spacing member, and means resiliently urging said elements towards said spacing member.

40 8. Apparatus as described in claim 7 further defined by a support frame, a bristle holder mounted on said frame for retaining unbent bristles, mounted on said support means frame for retaining a broom shoe, and universal mounting means for supporting said guide member on said frame and adapted for selective movement of said guide member between a position having said end of said guide member adjacent said holder and positions 45 wherein said end of said guide member is adjacent the apertures of the broom shoe.
